UNITED STATES PATENT OFFICE.

CHARLES CLINTON BURKE, OF NEW YORK, N. Y.

BARRELING PARAFFIN, &c.

SPECIFICATION forming part of Letters Patent No. 530,746, dated December 11, 1894.

Application filed October 15, 1894. Serial No. 525,878. (No model.)

To all whom it may concern:

Be it known that I, CHARLES CLINTON BURKE, a citizen of the United States, residing at New York, in the county of New York and 5 State of New York, have invented an Improvement in Barreling Paraffin and Similar Materials, of which the following is a specification.

The cakes of paraffin wax as they come from 10 the press are usually ground and packed into barrels, such as sugar barrels that are slack or not adapted to hold a liquid. In doing this it is necessary to remove one of the heads, and the paraffin so introduced is not solid 15 and a larger amount of such paraffin could be introduced into the barrel if in a melted condition, but in consequence of the barrel not being tight the melted paraffin is liable to run through the interstices, and this has 20 rendered it necessary heretofore to make use of more expensive and tight barrels where the paraffin is run into the same in a melted condition.

In some instances I have run paraffin wax 25 in a melted condition into barrels that are not tight and moved the barrel to cause the melted paraffin to flow around and adhere to the interior of the barrel and coat the same and close any interstices before the melted 30 paraffin is run into the barrel, for filling the same, but this involves the necessity of manipulating the barrel and is not always reliable.

My improvement relates to a method of reducing the temperature of the paraffin to the 35 crystallizing point or nearly so before running the melted paraffin into the barrel in order that the paraffin may congeal with sufficient rapidity to prevent it running through 40 any crevices in the barrel and thereby allowing for the use of less expensive barrels than has heretofore been necessary, and also introducing into such barrel as large a weight of paraffin as the same is capable of holding.

45 In the drawings, Figure 1 is a general elevation illustrating the apparatus made use of by me. Fig. 2 is a cross section of the pipe for supplying melted paraffin, on a larger scale.

The paraffin or similar material in a melted 50 condition is supplied into a suitable tank B

in any desired manner, and from this tank such melted wax passes by a pipe and cock 2 to the horizontal pipe F which is preferably of a sufficient size for the pipe C to pass through it, and this pipe C is to be heated 55 by steam or cooled by water or other material according to the condition of the paraffin, and should the paraffin become congealed in the pipe F, steam introduced through this pipe C can be made use of to melt or thaw 60 out such paraffin, and the end of the pipe F is closed around the pipe C by suitable stuffing boxes at 3 and valves may be made use of as at 4, to allow the melted paraffin to pass away when it is desired to empty the tank B 65 without allowing the melted wax to pass to the barrels, as next described.

The pipe F is of sufficient length to receive the hanging nipples and cocks D which may be opened and closed more or less at pleasure 70 and advantageously by rods 5 extending to near the floor, so as to be operated by the attendant, and the stream of melted paraffin is directed from each cock upon a spreader 7, so that the paraffin falls in drops or in a thin 75 sheet from the lower edge of such spreader 7.

The barrels L rest upon any suitable floor or platform K which may be raised or lowered if desired, and I prefer to stand such barrels upon their heads, so that the filling 80 operation may take place from the upper end or head of each barrel, and the melted paraffin is directed by the funnels or troughs M to the openings in the barrel at which movable funnels N are advantageously applied. 85

The distance between the cocks D and the funnels M is to be sufficient for the paraffin to be chilled as it falls through the atmosphere, and the distance of the fall should be greater in warm weather than in cold weather, 90 so that the paraffin when it reaches the funnels M is at a temperature corresponding or nearly so to the crystallizing point, and in order to vary the distance through which the paraffin falls, the platform K may be raised 95 or lowered, or the tank B and the pipe F therewith connected may be raised or lowered, or the volume of paraffin issuing from each of the cocks D may be regulated so that by the melted wax running slower there will be more 100

opportunity for the atmosphere to act in cooling the paraffin as it falls down from the spreader 7 to the funnel M or trough.

By the present improvement the paraffin will pass into the barrels at such a low temperature as to congeal by contact with the insides of such barrels, and hence the paraffin will seal up any cracks or interstices in the barrels and the paraffin will not flow out from the same; and I find it advantageous to fill the barrels through an opening in the top head and to set such barrels aside over night if possible, so that the paraffin has the opportunity to shrink and consolidate, and by bringing such barrels into position under the funnels M, paraffin can be supplied into such barrels to entirely fill the same so that there may be no lost space in transportation and the staves can be readily stripped off the block of paraffin when the same is to be made use of in the arts.

This improvement allows me to effect a great saving by employing barrels of inferior quality for receiving and shipping the paraffin, instead of being obliged as heretofore to use barrels that are substantially tight to prevent the melted paraffin running through the interstices.

If the attendant discovers that the wax in the barrels does not congeal with sufficient rapidity, the flow of the melted wax can be regulated by the rods 5 and cocks D. It will be apparent that the barrels might be filled through holes in the staves at the bilge if so desired.

By the present improvement a great saving is effected in the labor required in filling and packing the paraffin crystals into the barrels, and in consequence of the paraffin or wax being very compact within the barrels and the barrels entirely filled there is no loss in transportation.

In cases where a pump is used to elevate the paraffin the same may flow from the discharge pipe of the pump into the vessel or tank B, or it may pass directly into the pipe F by a pipe shown by dotted lines at S.

I claim as my invention—

1. The method herein specified of barreling paraffin or similar material, consisting in melting the paraffin, running the same from an elevated vessel, discharging the paraffin

in small streams or thin layers, allowing the same to fall through the atmosphere the necessary distance for parting with the required amount of heat and receiving such material into barrels at a temperature corresponding or nearly so to the crystallizing or consolidating point of the wax, substantially as set forth.

2. The combination in an apparatus for barreling paraffin and similar material, of an elevated tank for receiving the melted wax, a cock and horizontal pipe through which the paraffin is allowed to flow, discharge cocks connected with the horizontal pipe, barrels and funnels or troughs for directing the material into the barrels, such paraffin or similar material being allowed to fall through the atmosphere a sufficient distance for reducing the temperature of the melted wax to the point of crystallization or nearly so, substantially as set forth.

3. The combination in an apparatus for barreling paraffin and similar material, of an elevated tank for receiving the melted wax, a cock and horizontal pipe through which the paraffin is allowed to flow, discharge cocks connected with the horizontal pipe, and spreaders upon which the melted wax is received from the cocks, barrels and funnels or troughs for directing the material into the barrels, such paraffin or similar material being allowed to fall through the atmosphere a sufficient distance for reducing the temperature of the melted wax to the point of crystallization or nearly so, substantially as set forth.

4. The combination in an apparatus for barreling paraffin and similar material, of a pipe through which the paraffin is allowed to flow, discharge cocks connected with the pipe, barrels and funnels or troughs for directing the material into the barrels, such paraffin or similar material being allowed to fall through the atmosphere a sufficient distance for reducing the temperature of the melted wax to the point of crystallization or nearly so, substantially as set forth.

Signed by me this 8th day of October, 1894.

CHARLES CLINTON BURKE.
